UNITED STATES PATENT OFFICE.

JOHN ENDRESON, OF BROOKLYN, NEW YORK.

LIFE-BUOY.

1,332,171.

Specification of Letters Patent. Patented Feb. 24, 1920.

Application filed July 26, 1919. Serial No. 313,609.

To all whom it may concern:

Be it known that I, JOHN ENDRESON, a citizen of the United States, residing at Brooklyn, in the county of Kings and State 5 of New York, have invented new and useful Improvements in Life-Buoys, of which the following is a specification.

This invention relates to improvements in life buoys and means for supporting the 10 same in position on a vessel from which the buoy may be readily dropped over board astern of the vessel in order to enable a person who has fallen over board to readily reach the buoy.

15 Heretofore, life buoys were secured at spaced intervals to the sides of a vessel and were designed to be thrown over board by parties on deck but owing to the forward position of the buoy and the speed of travel 20 of the vessel a man has frequently been lost owing to his inability to reach the buoy as it has been impossible to launch the buoy in time to permit the throwing of the same into close proximity to the party over 25 board. Therefore, I provide a launching device at the stern of the vessel from which this improved buoy may be launched so that should a man fall over board from a point intermediate the length of the vessel the 30 buoy may be released and will strike the water about the time the vessel passes the party, thus giving him a better opportunity of reaching the buoy.

Another object of the invention is to provide 35 a signal flag which is automatically elevated to signaling position when the buoy is launched and to provide a signal light which is thrown into automatic operation when the buoy strikes the water.

40 A still further object of the invention is to provide ladders on the buoy which are designed to permit a person in the water to easily enter the buoy and which may be also connected to a tackle when the buoy 45 is being hoisted aboard a vessel.

As a further object the invention consists in a novel form of cradle and release mechanism for the buoy by means of which the same may be launched from the bridge.

50 With these and other objects in view the invention consists in the novel construc-

tion, combination and arrangement of parts which will be fully set forth in the following specification, claimed and illustrated in the accompanying drawing, in which:

55 Figure 1 is a side view of a vessel equipped with this improved launching device.

Figure 2 is a top plan view of the buoy.

Figure 3 is a longitudinal sectional view 60 therethrough.

Figure 4 is a longitudinal sectional view 65 through the launching device, and

Figure 5 is a fragmentary view partly in section of one of the pontoons of the buoy 65 showing the alarm mechanism.

Figure 6, is a perspective view of the buoy 70 just after being released from the cradle, the signals being brought into play.

Figure 7, is a perspective view of the buoy 70 illustrating the manner in which it may be brought back to its cradle.

Figure 8, is a detail view of the device for holding the signal flag in an upright position.

75 Figure 9, is a detail view of the buoy releasing means.

Referring to the drawings in detail, the numeral 1 designates a vessel of ordinary construction having the usual bridge 2 and 80 masts 3. Secured to the upper deck of the vessel at the stern is a cradle 4 upon which the buoy is supported preferably in an inclined position. The sides of the cradle 4 are provided with rollers 5 which serve 85 to guide the buoy out of the cradle and from between the sides thereof and for facilitating the launching of the buoy. Secured between the uppermost rollers of said cradle is the buoy hanger designated 90 generally by the numeral 6 which comprises a base 7 having attached to its upper side a pair of spaced angle irons 8 which are bridged by straps 9. Slidably mounted on the upper edges of the angle irons and beneath the bight portions of the straps is a sliding bolt 10 provided intermediate its ends with a stop pin 11. A hook 12 is pivoted between the angle irons at one end and is provided with an extension which 95 normally lies beneath the bolt in order to hold the hook in securing position. Re-

tractile coil springs 13 are secured to the bolt and normally tend to hold the same in such position as to overlie the extension on the hook hereinbefore described. Attached to the end of the bolt opposite that which overlies the extension on the hook is a flexible member or cable 14 which extends upwardly and forwardly over the stern mast and through the rigging to a point on the bridge 2 from which the movements of the flexible member and bolt may be controlled.

The buoy above referred to comprises a pair of pontoons 15 which may be of any preferred construction and which are connected adjacent opposite ends by pairs of spaced connecting bars 16 to which a suitable netting 17 is secured. This netting is arranged in the manner illustrated in the drawing to provide a pocket into which a person may climb and secured to the outermost bars 16 are rope ladders 18 to facilitate the entering of the buoy. Secured to one of the pontoons 16 is a pair of straps 19 beneath which an angular extension of a flag staff 20 is pivotally secured and attached to the free end of said flag staff is a signal flag 21. A bracket 22 having a bifurcated head 23 is secured to the pontoon 30 to which the straps 19 are attached and is arranged so that when the flag staff moves to a vertical position it will be received between the bifurcations of the head. Suitable spring actuated latches 24 are arranged in said head and are designed so that the flag staff will be free to move into the head but after having been seated therein will be prevented from falling outwardly by said latches. A flexible member 25 is connected 40 to the flag staff 20 and carries at its free end a light 26 now in use in connection with the ordinary hand life buoy. The light 26 embodies a protective casing provided with a loop which is adapted to be connected to a hook 27 attached to the cradle at a point preferably shown in the drawing. As the buoy is launched the flexible member 25 will be constrained, causing the protective casing of the light to break thereby causing the light to be ignited. The light hangs in the water at one end of the flexible member 25 and by reason of the substance within the same being exposed to the action of the water, there will be generated a gas 55 which burns continuously setting up a flame which readily attracts attention. The resistance offered by the protective casing of the light 26 until it breaks, sufficiently constrains the flexible member 25 so as to cause 60 the flag staff 20 to move to a vertical position and to be received between the latches 24 carried by the head of the bracket 22 to be held thereby in an upright position. It will be understood that both of the visual

signals will be operated simultaneously by virtue of the launching of the buoy.

As a further precaution an audible signaling means is provided. This audible signaling means is attached to one of the pontoons 15 and consists of, among other things, a suitable housing 28 for containing a bell and suitable batteries by which the bell is actuated. A switch 29 is arranged in the bell circuit and the lever 29^a thereof has connected to one end a flexible member 30 which embodies an element 30^a made up of two component parts adapted to be separated when the member 30 is constrained to a predetermined degree. The opposite end of the member 30 is connected to the cradle shown in the drawings. When the buoy is launched the flexible member 30 will be constrained causing the lever 29^a to move to close the circuit thereby causing the sounding of the bell. The component parts of the device 30^a will be separated as the member is constrained, the device offering sufficient resistance before separating to move the lever 29^a to the circuit closing position. If desired suitable containers 31 for food and drinking water may be secured to one or both of the pontoons and each of said pontoons is provided with a hand rail 32.

In operation it will be readily seen that the buoy is mounted on the rollers 5 of the cradle 4 in such a manner that the hook 12 engages one of the cross bars 16. It will be understood that the ladders 18 and the netting 17 is folded into the space between the pontoons. Upon the detection from the bridge of a man over board, pull is exerted on the flexible member 14 thereby moving the bolt 10 out of engagement with the extension on the hook 12 thereby allowing the same to rock to releasing position and permitting the buoy to slide downwardly from its position on the cradle. The movement of the buoy downwardly will cause the flexible members 25 and 30 to become distended thereby automatically throwing all of the signals into operation so as to readily enable the buoy to be located.

When it is desired to hoist the buoy aboard, the rope ladders 18 are swung upwardly so that the loops at their free ends may be hooked through a tackle and thus form a bail by which the buoy may be elevated.

While in the foregoing there has been shown and described the preferred embodiment of this invention it is to be understood that certain minor changes in the details of construction, combination and arrangement of parts may be resorted to without departing from the spirit and scope of this invention as claimed.

What is claimed as new is:—

1. In a device of the class described, the

combination of a cradle, a buoy adapted to be releasably mounted on said cradle, a buoy releasing means, signals carried by said buoy, signal operating means, breakable connections between the cradle and said operating means for rendering the signals active upon the release of the buoy from its cradle.

2. A device as characterized, including a

cradle for supporting a releasable pontoon- 10 buoy in an inclined position, and rollers carried by the cradle for guiding the buoy out of the cradle upon its release and facilitating the launching of the buoy.

In testimony whereof I have affixed my 15 signature.

JOHN ENDRESON.
